JOHN R. WEBER, OF BOURBON, INDIANA.

Letters Patent No. 71,932, dated December 10, 1867.

IMPROVEMENT IN CORN-PLANTER.

The Schedule referred to in these Letters Patent and making part of the same.

TO ALL WHOM IT MAY CONCERN:

Be it known that I, JOHN R. WEBER, in the county of Marshall, and State of Indiana, have invented a new and improved Corn-Planter; and I do hereby declare that the following is a full and exact description of the same, reference being had to the accompanying drawings, and to the letters of reference marked thereon.

Figure 1 represents a right-hand view of my invention.

Figure 2, a left-hand view.

Figure 3, a top view, with the seed-dropping arrangement removed, and

Figure 4 a front view.

This invention consists of a novel arrangement for effecting the dropping of grains of corn into the rows; also for raising and lowering the ploughs, and for various other purposes, as will hereinafter more fully appear.

To enable others to make and use my invention, I will now proceed to describe its construction and operation.

A represents the framework of the machine, supported on the wheels *a a* and the caster-wheel *b*. The framework A is made in two parts, one part bearing one set of ploughs and one wheel, *a*, and the other part bearing the other set and the other wheel, *a*, and both parts being connected by transverse rods, *c*, provided with screw-threads and nuts, by means of which they can be made to approach or recede from each other, and the distance between the two rows made to vary from three and a half to four feet at pleasure. Projecting vertically upward from the outer rails of the frame A are standards, *d d*, the upper ends of which contain sockets for the reception of the ends of the transverse shaft *e*. Attached to the inner sides of the standards *d* are elastic metallic strips, *h h*, which sustain the tubes *i i*, which surround the dropping-cylinders *k k*, fastened near the ends of the transverse shaft *e*. The tubes *i* support the hopper-shaped receivers *k' k'*. The dropping-cylinders are each provided with four radial holes for the reception of the seed. Each hole, in its turn, passes under the orifice of the receiver *k*, and receives the proper number of grains therefrom. At the end of a half revolution of the cylinder, the hole becomes inverted directly over the mouth of the tube *l*, and the grains fall out into said tube, through which they fall into the furrow. The number of grains each hole receives is regulated by a disk in each, attached to one of the springs, *m*, on the shaft *e*. To one end of this shaft is rigidly secured a block, *n*, from each corner of which projects a pin, *o*. A hook, *r*, which engages with the pins *o* in succession, is pivoted to the sliding bar *s*, which plays back and forth along the side of the machine, through the medium of the slots *t t* and pins in the standards *u u*, which pass through the slots. The motion of the bar *s* is communicated, by means of the hook *r* and pins *o*, to the block *n*, shaft *e*, and dropping-cylinder *k*. The hook *r* is provided with a spear-head, that it may easily slip past the pins *o* on its return throw. A T-shaped bar, *u*, attached to a horizontal rod that receives a reciprocating motion parallel to the bar *s*, is held in contact with the block *n* by a spiral spring, and operates to bring the block around, so that its sides shall be vertical, and so that the hook *r* shall always come in contact with one of the pins *o*.

The motion of the sliding bar *s* is derived from the rotation of the transverse shaft *v*, provided with a crank, *w*, which has a friction-roller that, during the revolution of the crank, comes in contact with the arm *x*, projecting downward from the bar *s*. The arm *x* is pivoted to the bar *s*, and is provided with the arm *a'*, projecting from it at right angles, against which bears the spring *b'*. This spring is sufficiently strong to sustain the pressure brought by the striking of the crank *w* against the arm *x* long enough to insure the sliding back of the bar *s* to a due degree. On the opposite side of the arm *a'* from the spring *b'* is a pin, *c'*, against which the arm *a'* brings up whenever the crank *w* revolves in the opposite direction, and stops its revolution with that of the shaft *r*. A spiral spring, *d'*, attached to the end of the bar *s* opposite that where the hook *r* is attached, insures the return throw of the bar *s* after the passage of the crank. The motion of the shaft *v* is obtained from the pinion *e'* on the opposite end from the crank *w*, said pinion gearing with the toothed wheel *h'* rigidly attached to and concentric with the axle of the wheel *a*. B represents a smaller frame, pivoted to the transverse shaft, *k*, on the front part of the machine, said shaft being supported by standards, *l'*, above the main frame A. Two elbow-levers, *m' m'*, the fulcra of which are on the transverse shaft *k*, are attached, at their upper ends, to the rear part of the frame B, and are jointed, at their lower ends, to the ends of rods *n' n'*, which are pivoted, at their opposite ends, to arms *o' o'*, projecting from the short transverse shafts *r' r'*, one on each side of the

machine. Similar rods, $s' s'$, connect the arms $o' o'$ with the arms $t' t'$; on the similar short transverse shafts $u' u'$, in rear of the shafts $r' r'$. The latter sustain the furrowing-ploughs $v' v'$, of which there are two, one on each shaft; and the shafts $u' u'$ sustain the covering-ploughs $w' w'$, of which there are four, two on each shaft. This machine thus furrows and covers two rows at a time. The ploughs are suitably braced by rods x' .

It will be seen that, by depressing the rear end of the frame (which may be done by the foot of the driver) through the mechanism of the elbow-levers $m' m'$, the connecting-rods $n' n'$ and $s' s'$, the arms $o' o'$ and $t' t'$, and the shafts $r' r'$ and $u' u'$, the ploughs may be elevated; and, by elevating the same, the ploughs may be depressed within certain limits. The shafts $r' r'$ and $u' u'$ are attached, by means of screws, u'' , to the frame A; and their distance from the ground may be regulated in this way. a'' represents a lever, pivoted, at b'' , on the side of the machine, and attached, at its rear end, to the shaft v , which latter is kept ordinarily in place by the spring e''' . By depressing the forward end of the lever a'' , the pinion e' is raised out of gear with the toothed wheel h' . This being done, the seed-dropping apparatus ceases to operate, and the machine may be drawn from place to place without wear of said apparatus. The foot-board c'' is also pivoted to the transverse shaft k'' . Its rear side rests upon the lever d'' , the forward part of which is bifurcated, as seen at $m'' m''$. Vertical rods, $e'' e''$, connect the forks d'' with the ends of the cross-piece, h'' , just below the front part of the frame. In this cross-piece is a groove, h''' , at the centre for the tongue l'' , which is attached to the frame of the caster-wheel b .

By depressing the rear side of the foot-board c'' , through the mechanism of the bifurcated lever $d'' m''$ and the connecting-rods e'' , the cross-piece h'' may be disconnected from the tongue, which may then be turned to the right or left to any extent desired, and the machine turned within a very small space.

The ends of the forks d'' , and of all the cross-braces, n'' , of the machine, are provided with slots, in order not to interfere with the adjustment of the side frames at greater or less distances from each other, as may be desired.

Having thus fully described my invention, what I claim as new, and desire to secure by Letters Patent, is—

1. The springs, m , on the shaft e , in combination with the dropping-cylinders k , as and for the purpose described.
2. The combination of the foot-board c'' , forked lever $d'' m''$, connecting-rods e'' , and cross-piece h'' , arranged and operating as explained.
3. The combination of the frame B, elbow-levers m' , connecting-rods $n' s'$, arms $o' t'$, and shafts $r' u'$, as and for the purpose set forth.
4. The combination of the transverse shaft v , sliding bar s , hook r , pins o , block n , and dropping-cylinders k , substantially as described.
5. The combination of the crank w , arm $x a'$, spring b' , and sliding bar s , arranged and operating as set forth.
6. The combination of the lever a'' , shaft v , pinion e' , and spring e''' , when used independently, or in connection with the frame B, substantially as and for the purpose described.

JOHN R. WEBER.
